UNITED STATES PATENT OFFICE.

EMIL HUBNER, OF NEW YORK, N. Y.

BOLT-HEADING DEVICE.

SPECIFICATION forming part of Letters Patent No. 427,324, dated May 6, 1890.

Application filed February 25, 1890. Serial No. 341,709. (No model.)

To all whom it may concern:

Be it known that I, EMIL HUBNER, of New York city, in the county and State of New York, have invented a new and Improved 5 Bolt-Heading Device, of which the following is a full, clear, and exact description.

My invention relates to improvements in bolt-heading devices adapted for use in connection with any bolt-making machine operated by a lever or treadle, and has for its object to provide a means whereby a bolt may be headed in an effective and expeditious manner and with the least possible manipulation of the metal rod from which the bolt 15 is to be formed.

A further object of the invention is to construct the device in such a manner that the sections of the gripper will be interchangeable, and wherein each and every part will 20 be of maximum strength.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a central vertical section through a machine having the device applied, the said section being taken on line 1 1 of Fig. 2. Fig. 2 is a plan view of such a machine. Fig. 3 is a plan view of the device detached from the machine. Fig. 4 is an end view of one of the gripper-sections and the heading-die or former upon the line 4 4 of Fig. 3. Fig. 5 is a side view of the gripper, illustrating the recess in which the heading-die or former has play, the 35 said heading-die or former being removed, and the view as taken being upon the line 5 5 of Fig. 3. Fig. 6 is a perspective view of one section of the gripper. Fig. 7 is a perspective view of the heading-die or former, looking at the under side, the said die or former being adapted for making rectangular bolt-heads; and Fig. 8 is a similar view of a former 45 adapted for use in the construction of hexagonal bolt-heads.

The gripper A is constructed in two sections *a* and *a'*, both of said sections being preferably of equal size. In the longitudinal

sides of each section at one end an essentially L-shaped recess 10 is made, and the said sides are further provided with a semi-circular groove or channel 11, extending from the base-wall of the recesses to the opposite end of the section. The construction of both longitudinal sides of each section is identical, whereby they may be used interchangeably, 55 if desired.

The heading-die or former B consists of a head 12, substantially rectangular in cross-section and of greater length than width, and an attached or integral shank-section 13, which 60 is preferably conical and is adapted to enter any suitable form of chuck or its equivalent. The head 12 is of sufficient width only to move freely in the recess 10 of the gripper, where the two sections are placed together, as illustrated in Fig. 3, whereby a rectangular recess 65 is formed. The length of the head of the heading-die or former is, however, much greater than the width of the gripper, as illustrated in Fig. 4. In fact, the heading-die extends outward beyond each side face of the 70 gripper.

In the under or working edge of the head of the die or former a recess 14 is produced, extending from side to side, the side and top 75 walls of which recess are straight and smooth; but the surface at the junction of the side and base walls of the recess is inclined or beveled, as illustrated at 15 in Fig. 7, the said bevel being adapted to form a chamfered surface upon the head of the bolt. By reference to Fig. 7 it will be observed that the recess 80 14, being essentially rectangular, is adapted for use in the construction of square-headed bolts.

When a hexagonal bolt-head is to be made, the form of die illustrated in Fig. 8 is employed, in which the side walls of the recess 85 14 are angular, and when other forms of bolt-heads are to be made the recess or cavity 14 in the former or die head is made to correspond.

In Figs. 1 and 2 I have illustrated one form of machine to which the device may be applied, and which will illustrate the operation 90 of the device. The machine consists of a skeleton table 16, having ways 17 produced in the inner side surfaces, which ways are adapted to act as guides for a combined cam

and plunger 18, the cam being located at one side of the machine and the plunger at the other side, the plunger being adapted to carry forward a sliding chuck 18^a, the said chuck being purposed to receive the heading-die or former B. To the rear end of the plunger an arm 19 is hinged, which is normally held in an upper position at an angle to the said plunger by a spring 20, attached thereto and to a bracket 21, projected from the rear portion of the bed. Beneath the bracket in the bed a shaft 22 is held to revolve, carrying a cam 23, so located that when the arm 19 is lowered or depressed the said cam will come in contact with the rear end of the arm and force the plunger and its cam forward. The arm 19 is depressed through the medium of a crank-lever 24, as illustrated in Fig. 2. The cam attached to the plunger is adapted to engage with a vertical rocking bar 24^a, which is pivoted beneath the table, as illustrated in Fig. 1, the upper end of the bar being adapted to extend upward flush with or beyond the table at one end, for a purpose hereinafter described, and the said rocking bar is normally drawn in the direction of one side of the table by means of a spring 25, attached to the table and to the upper portion of the said bar. Immediately at one side of the upper end of the rocking bar 24^a one section of the gripper is held to slide upon the bed between one end surface of the bed and a guide-strip 26, the said section being held to place through the medium of a strap 27 or equivalent device. The other section of the gripper is made to abut in proper manner against the section just described, and that section which contacts with the rocking bar is capable of lateral movement, the other sections being rigidly secured to the table. It will be observed, as heretofore stated, that when the two sections of the grippers are brought together a rectangular recess is formed in one side surface, and this recess, when the grippers are placed in position, is immediately opposite the chuck 18^a. Consequently when the heading-die or former is secured in said chuck and the plunger moves in the direction of the grippers the die will be forced farther into the gripper-recess, as the die or former during the entire operation of the machine never leaves the gripper-recess. It will be further observed that when the opposed channels 11 of the gripper-sections are brought together a round bore is the result.

In operation a rod of round heated metal is inserted in the central bore of the gripper when the section a is slid to one side, which is the case when the plunger is carried in the direction of the end of the bed opposite that at which the grippers are located. The inner end of the metal bar inserted in the grippers is introduced into the recess or cavity 14 of the heading-die or former, and after the grippers have been closed the plunger moves forward and the metal in the recess 14 is upset and four sides of the bolt-head are partly formed.

As the plunger moves backward, the section a of the gripper is again loosened, whereupon the metal is again pushed against the base-wall of the recess 14 to complete the formation of the bolt-head, as in the first operation enough stock is not obtained to form a perfect head. This second operation usually leaves a fin upon two sides of the head, which is removed by the next step, which consists in drawing the bolt-head from the die, giving the former a quarter-turn, and inserting the head once more in the die. This latter operation may be repeated as often as it may be found desirable. Ordinarily, however, the head is turned but three times, and at each turn is kept in contact with the walls of the recess 14 at each side of the bore, in order to provide a perfectly-smooth under face for the head.

I desire it to be distinctly understood that I do not confine myself to any form of machine, as heretofore stated, as the heading device, which is virtually a tool, is applicable to any form of machine upon which bolts are constructed, especially machines operated by a lever or treadle.

Having thus described my invention, I claim as new and desire to secure by Letters Patent—

1. In a bolt-heading device, the combination, with a gripper constructed in two sections, each section at one end upon each side being formed with an essentially L-shaped recess and a circular longitudinal channel, of a heading-die or former having a recess formed in its under face open at the sides, the contour of the recess being made to conform with the contour of the bolt-head to be made, substantially as shown and described.

2. In a device for heading bolts, the combination, with a gripper formed in two sections, one of which is adapted to be stationary and the other movable, the opposed surfaces of the sections having an L-shaped recess formed in one end, and a semicircular longitudinal groove extending from the base-wall of the recess to the opposite end of the section, whereby when the sections are united a rectangular recess is produced open at the sides and intersected by a circular bore, of a die or former comprising a shank and head, the head being of a width corresponding to the width of the recess of the gripper and of greater length than the width of the sections, and provided in the edge which enters the gripper-recess with a recess open at its sides and conforming to the contour of the bolt-head to be made, the open sides of the die or former recess being normally closed by the side walls of the gripper-recess, substantially as shown and described, and for the purpose specified.

EMIL HUBNER.
